UNITED STATES PATENT OFFICE

150,504

DESIGN FOR A TRIPOD

Wolcott S. Kinnard, Milwaukee, Wis.

Application February 21, 1948, Serial No. 144,654

Term of patent 14 years

(Cl. D57—1)

To all whom it may concern:

Be it known that I, Wolcott S. Kinnard, a citizen of the United States, residing at Milwaukee, in the county of Milwaukee and State of Wisconsin, have invented a new, original, and ornamental Design for a Tripod, of which the following is a specification, reference being had to the accompanying drawing, forming part thereof.

Fig. 1 is a perspective view of a tripod in a closed position; and

Fig. 2 is a perspective view of the tripod in an extended position and viewed from the back of Fig. 1, showing my new design.

I claim:

The ornamental design for a tripod, as shown.
WOLCOTT S. KINNARD.
